UNITED STATES PATENT OFFICE.

STEPHEN C. MENDENHALL, OF RICHMOND, INDIANA.

CASTER.

SPECIFICATION forming part of Letters Patent No. 314,956, dated March 31, 1885.

Application filed September 8, 1884. (No model.)

To all whom it may concern:

Be it known that I, STEPHEN C. MENDENHALL, a citizen of the United States, residing at Richmond, in the county of Wayne and State of Indiana, (present business address 5 Cincinnati, Ohio,) have invented certain new and useful Improvements in Plate-Casters for Furniture, Trucks, and other Articles, of which the following is a specification.

10 The object of the present invention is to render applicable to plate-casters having two floor-wheels the oscillating movement described in my application filed on the 6th of September, 1884. To this end I form a floor-wheel axle 15 with a horizontal cylindrical arm journaled within a corresponding bearing in the lower end of the spindle, which is riveted at its upper end over a washer on the top of the furniture-plate in the ordinary manner. Said spindle is provided with a horizontal flange or 20 disk, which carries near its outer periphery an anti-friction roller located directly above the floor-wheel axis. The furniture-plate is provided with a downwardly-projecting rib, 25 forming a cup which surrounds and hides the anti-friction movement.

In order that my invention may be more fully understood, I will proceed to describe it with reference to the accompanying drawings, 30 in which—

Figure I is a perspective view of the rear of my improved caster. Fig. II is a vertical section of the top and the lower portion of the spindle, showing, however, the floor-wheel axle in elevation, with one of its wheels removed. Fig. III is a plan of the caster with the top plate removed.

The center of oscillation may be upon a line 40 lying in the horizontal plane of the floor-wheel axis, as here shown, or it may be situated at a point lying in a horizontal plane below said axle, as I have explained in my aforesaid co-pending application. The oscillating movement is obtained by providing said axle 45 1 with a horizontal arm, 2, cylindrical in form, as shown in Fig. II, to occupy a corresponding bearing in the lower end of the spindle 3. The arm 2 is held to its bearing by washer 4

and rivet 5. The latter may be formed in one with said axle and arm when the same are 50 made of malleable cast-iron. Upon the spindles 6 of the axle 1 are journaled the floor wheels or rollers 7.

At its top the spindle 3 is riveted over a washer, 8, situated in a socket in the furniture-plate 9. The swiveling motion of the caster is between the cylindrical portion 10 of the spindle and the neck 11 projecting downward from the furniture-plate. Said furniture-plate is provided with a circular downwardly-projecting rim, 12, inclosing the anti-friction movement. This movement consists of a roller, 13, having bearing on the furniture-plate, and journaled in lugs or brackets 14, cast on the upper surface of a flange or projection, 15, 60 formed on the spindle 3. The best swiveling motion of the caster is obtained, while the strain on the spindle is avoided, by placing the anti-friction roller 13 in a line vertically 65 above the axis of the floor-wheels, as indicated 70 by the dotted line in Figs. II and III.

Having thus described my invention, the following is what I claim as new therein, and desire to secure by Letters Patent—

1. In combination with a floor-wheel, the 75 axle thereof having horizontal cylindrical arm, a vertical spindle in the bottom of which said arm is journaled, a flange or projection on said spindle, and a single vertical anti-friction roller supported on said flange vertically over 80 the floor-wheel axle, substantially as set forth.

2. In combination with a furniture-plate having a circular downwardly-projecting rim, a vertical spindle swiveled in said plate, a circular flange formed on said spindle, vertical 85 anti-friction movement supported on said flange and rolling on the furniture-plate, two floor-wheels and their axle having a horizontal arm bearing in the lower end of said spindle, so as to have liberty of oscillating movement, substantially as shown and described. 90

STEPHEN C. MENDENHALL.
